(57) **CLAIM**

The ornamental design for a remote with illuminated region, as shown and described.

DESCRIPTION

FIG. 1 is a front perspective of a remote with illuminated region in a non-illuminated state showing our new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a front perspective of the remote of FIGS. 1-7 showing the illuminated region in an illuminated state; FIG. 9 is a front view thereof; FIG. 10 is a rear view thereof; FIG. 11 is a left side view thereof; FIG. 12 is a right side view thereof; FIG. 13 is a top view thereof; and, FIG. 14 is a bottom view thereof.
The broken lines show portions of the remote with illuminated region that are not part of the claimed design. The radiating lines emanating from the circle in FIGS. 8-14 represent illumination.

1 Claim, 8 Drawing Sheets
